UNITED STATES PATENT OFFICE.

JOHN NORDIN, OF MONTICELLO, MINNESOTA.

MAIL-BOX SIGNAL.

Application filed November 27, 1925. Serial No. 71,641.

This invention relates to signals for mail boxes, and the primary object is to provide means of a novel and practical nature for automatically raising a signal when the door 5 of the box is opened, so that the farmer or other owner who may live at some distance from the box can tell when mail has been placed in the box by the postman, without going to and opening the box. Further and 10 more specific objects will be disclosed in the course of the following specification, reference being had to the accompanying drawing, in which:

Fig. 1 is a perspective view of a well 15 known type of mail box, the same being provided with my improved signal.

Fig. 2 is a perspective view similar to Fig. 1, but showing the signal in a raised position.

Fig. 3 is a top view of the box as shown in Fig. 2.

Fig. 4 is a modification showing the application of my invention to a mail box having an upwardly swinging door, as distinguished from the downwardly opening door shown in Figs. 1, 2 and 3.

Fig. 5 is an end view of the box shown in Fig. 4, and showing the signal as raised.

Referring to the drawing more particularly and by reference character, A designates a common type of mail box having a door B which hinges as at C and clasps shut as at D. Upon one side of the box A is pivotally secured, as at 6, a lever 7, having a weight 8, at its rear end, and a signal or flag 9, at its front end. The flag 9 is preferably curved, as shown, and not flat, so that when it is in a raised position it can readily be seen from a distance even when the observer is directly in front or behind it, which could not of course be done if the flag were

straight or flat. The lever is held down or in a horizontal inactive position by a pin or extension 10 on the door. Thus, when the postman opens the door B, to place mail in the box, he automatically releases the pin 10 from the lever 7, permitting the weight 8 to fall and raise the flag 9. When the owner then removes the mail he replaces the lever to the position shown in Fig. 1.

In the modification shown in Figs. 4 and 5 the box E is of the type having an upwardly swinging cover F, which is hinged as at G. The lever 7 is pivoted on one end of the box and has a notch 11 for locking engagement with the cover pin 12. The opening of the cover releases the signal in substantially the same manner as in the box shown in Figs. 1, 2 and 3.

It is understood that suitable modifications may be made in the general design and structural details of the invention as herein shown and described, provided, however, that said modifications come within the spirit and scope of the appended claim.

Having now therefore fully shown and described my invention, what I claim to be new and desire to protect by Letters Patent is:

A mail box having a hingedly secured door, a stop member projecting laterally from the door, a lever pivoted to the side of the box and having freedom for complete rotating movement, said lever having a relatively long signal carrying end for releasable engagement with said stop, and a relatively short, weighted end adapted to be passed by the stop without abutting the same when the door is closed.

In testimony whereof I affix my signature.

JOHN NORDIN.
